UNITED STATES PATENT OFFICE.

WAYNE WILLIAM BISSELL, OF ROCHESTER, MINNESOTA.

STUMP-PULLER.

1,399,244.

Specification of Letters Patent.

Patented Dec. 6, 1921.

Application filed June 30, 1920. Serial No. 392,934.

To all whom it may concern:

Be it known that I, WAYNE W. BISSELL, a citizen of the United States, and a resident of Rochester, in the county of Olmsted 5 and State of Minnesota, have invented a new and useful Improvement in Stump-Pullers, of which the following is a full, clear, and exact description.

My invention relates to devices for pulling 10 stumps, and it consists in the combinations, constructions and arrangements herein described and claimed.

An object of my invention is to provide 15 a device for pulling stumps on an extensive scale, and to this end the apparatus is so arranged as to permit the pulling of a plurality of stumps at one time.

A further object of my invention is to provide an arrangement by means of which the 20 stumps are pulled from opposite directions, so that the stumps on one side of the device afford an anchorage for pulling the stumps on the other side of the device.

A further object of my invention is to 25 provide a stump pulling device which is in the nature of a tractor having an engine for operating the same, with a plurality of drums for drawing in the cables by means of which the stumps are pulled, each of the 30 drums being controlled independently.

A further object of my invention is to 35 provide a stump pulling device having auxiliary drums by means of which the cables of the stump pulling drums may be run out from the drums to the point at which the stumps are located.

A further object of my invention is to 40 provide a device of the type described in which the stump pulling capacity is greatly augmented, due to the fact that it has a greater radius of operation over that of the ordinary stump puller which has to be anchored and which pulls in one direction only.

Other objects and advantages will appear 45 in the following specification, and the novel features of the invention will be particularly pointed out in the appended claims.

My invention is illustrated in the accompanying drawings, forming part of this 50 application, in which—

Figure 1 is a side view of the device,

Fig. 2 is a plan view,

Fig. 3 is a front view,

Fig. 4 is a sectional view substantially on 55 the line 4—4 of Fig. 2,

Fig. 5 is a detailed view of the friction head,

Fig. 6 is a diagrammatic view showing the manner in which the stump pulling cable is 60 run out by the auxiliary drums, and

Fig. 7 is a diagrammatic view showing the manner in which the stumps are pulled in clusters on opposite sides.

In carrying out my invention, I provide 65 a tractor mechanism of any approved type, such as that of the so-called Holt caterpillar type. The tractor feature forms no part of the invention, except in so far as it coöperates with the stump pulling mechanism 70 to produce the result desired.

In the drawings I have shown a frame 1 upon which is mounted a boiler 2. Steam engines 3 and 4 of any approved type are mounted on opposite sides of the boiler on 75 suitable supports 5. In Fig. 1 it will be seen that the piston rod 6 of the engine 4 is connected with a cross head 7, which is in turn connected by a pitman 8 with a wheel 9 on a crank shaft 10. On the opposite side of 80 the boiler the engine 3 is connected by similar parts numbered 6' to 9' inclusive with a shaft 10 bearing a gear 11' in mesh with a drive gear 12' on a shaft 13. The latter has a sprocket wheel 14' which is connected by 85 a chain 15' with a sprocket wheel 16' on the shaft 17' (see Figs. 2 and 4). A companion shaft 17 bears a sprocket wheel 16 which is driven by the engine 4. Clutches 18 and 18' on the shafts 17 and 17' are provided for 90 throwing into action sprocket wheels 19 and 19' respectively. Sprocket chains 20 and 20' drive sprocket wheels 21 and 21' respectively on a drive shaft 22 for operating the tractor mechanism.

Referring now to Fig. 2, it will be seen that I have provided a gear 23 on the shaft 17, in mesh with a bevel gear 24 on a shaft 25, mounted in bearings 26 on the frame 27. The shaft 25 bears a gear 28 in mesh with 100 a gear 29 secured to a drum 30 which is rotatably mounted on bearings 31. The shaft 25 is provided with a coupling 32 (see Fig. 4) by means of which the gear 28, which is loosely mounted on the shaft, may be 105 brought into operation. A similar coupling 33 brings into operation a gear 34 which engages a large gear 35 on the shaft of an auxiliary drum 36 rotatably mounted in the bearings 31. On the opposite side of the 110 device is a mechanism which includes the elements 23' to 36' inclusive which are iden-

tical with the elements 23 to 36 inclusive, just described. It will be noted that the drums are disposed on axes which are parallel with the longitudinal axis of the vehicle.

Referring now to Figs. 3 and 5, it will be seen that the shaft 13 upon which the sprocket wheels 14 and 14' are mounted has a friction clutch mechanism by means of which the gears 12 and 12' may be operatively connected so as to drive the sprockets. This mechanism consists of a friction head having a female member 37 which is arranged to be frictionally engaged by a male member 38, the latter being secured to the gear 12 and being operated by toggles 39 which are actuated by a movable sleeve 40 when the handle 41 is turned. Power may thus be transmitted through the sprockets 14 and 14' and through the chains 15 and 15' at will, since the opposite end of the device has a similar friction clutch mechanism.

From the foregoing description of the various parts of the device, the operation thereof may be readily understood. Let us assume that the stump pulling device is at the position marked A in Fig. 6, and that the stumps have been pulled from an area on each side thereof, and it is now desired to pull the stumps in the area C. A light cable 42 is carried out around the snatch blocks or pulleys 43, 44 and 45 by means of a horse or in any other suitable manner, and then back to one of the drums, such as drum 30'. The end of the small cable 42 is fastened to the end of the cable 46 on the drum 30, and the auxiliary drum 36' is set into motion to wind up its cable 42, thereby drawing out on the heavier cable 46 to the area C, where the stumps are to be pulled. The actuation of the auxiliary drum is effected by throwing in the clutch 33 (see Fig. 4), the clutch 32 being disengaged so that the drum 30 is idle while the auxiliary drum 36 is being actuated. The device is moved forward under its own power by throwing in the clutches 18 and 18' (see Fig. 2) until it reaches the position B. The cable 46 is then secured by branch cables or chains to the various stumps in the area. The cable 46' on the opposite side is drawn out in the same manner and attached to the stumps on the opposite side of the device. The auxiliary drums 36 and 36' are now disengaged by throwing out the clutches 33 and 33', and the drums 30 and 30' are set in motion by throwing in the clutches 32 and 32'. The stumps are thus pulled from opposite directions, the stumps on one side of the machine serving as an anchorage for pulling the stumps on the other side of the machine. This obviates the necessity of anchoring the stump pulling device itself. Where stumps are pulled on a large scale, it will be obvious that this is a great saving of time as well

as of labor. The pulling of stumps from opposite sides of the machine also vastly increases the efficiency of the machine, because it doubles its area of operation. It is at times desirable to cut off the power from one side or the other, and in this respect the machine has all of the necessary adjustments. By means of the handles 41 and 41', either of the gears 12 or 12' may be put into or out of commission through the operation of the friction clutches, such as that shown in Fig. 5, and as above stated, either side of the traction driving device may be connected or disconnected by means of the clutches 18 or 18', while the clutches controlling the various drums can be manipulated so as to bring any drum into or out of use.

I claim:

1. A stump pulling device comprising a vehicle, a plurality of drums carried thereby and disposed on axes parallel to the longitudinal axis of the vehicle, cables carried by said drums and adapted to be drawn out on opposite sides of the vehicle, and means for operating said drums to draw in said cables. 85

2. A stump pulling device comprising a vehicle, a plurality of drums carried thereby and disposed on axes parallel to the longitudinal axis of the vehicle, cables carried by said drums and adapted to be drawn out on opposite sides of the vehicle, an engine, and means connecting said engine with said drums for operating the latter to draw in said cables. 95

3. A stump pulling device comprising a vehicle, a plurality of drums carried thereby and disposed on axes parallel to the longitudinal axis of the vehicle, cables carried by said drums and adapted to be drawn out on opposite sides of the vehicle, an engine, 105 means connecting said engine with said drums for operating the latter to draw in said cables, and means for disconnecting either drum at will.

4. A stump pulling device comprising a vehicle, a plurality of drums carried thereby and disposed on axes parallel to the longitudinal axis of the vehicle, cables carried by said drums and adapted to be drawn out on opposite sides of the vehicle, an engine, 115 means connecting said engine with said drums for operating the latter to draw in said cables, means for disconnecting either drum at will, and power means for drawing out the cables of each drum. 120

5. A stump pulling device comprising a vehicle, a plurality of drums carried thereby and disposed on axes parallel to the longitudinal axis of the vehicle, cables carried by said drums and adapted to be drawn out 125 on opposite sides of the vehicle, an engine, means connecting said engine with said drums for operating the latter to draw in said cables, means for disconnecting either drum at will, and an auxiliary drum con- 130

nected with each of said cable drums for drawing out the cable.

6. A stump pulling device comprising a vehicle, a plurality of drums carried there-
5 by and disposed on axes parallel to the longitudinal axis of the vehicle, cables carried by said drums and adapted to be drawn out on opposite sides of the vehicle, an engine, means connecting said engine with said 10 drums for operating the latter to draw in said cables, means for disconnecting either drum at will, an auxiliary drum connected with each of said cable drums for drawing out

the cable, and means adapted to be connected with the engine for causing the operation of each of said auxiliary drums at will. 15

7. A stump pulling device comprising a vehicle, rotative cable carrying means mounted on said vehicle on an axis parallel 20 with the longitudinal axis of the vehicle, and cables carried by said cable carrying means and adapted to be drawn out on opposite sides of the vehicle.

WAYNE WILLIAM BISSELL.
